[57] CLAIM

The ornamental design for a sneeze shield assembly, as shown and described.

DESCRIPTION

FIG. 1 is a front perspective view of a sneeze shield assembly showing my new design; the broken lines are for environmental purposes only and form no part of the claimed design;

FIG. 2 is a front elevational view of the sneeze shield assembly showing my new design;

FIG. 3 is a top plan view thereof;

FIG. 4 is a side elevational view of one side thereof;

FIG. 5 is a side elevational view of the other side thereof;

FIG. 6 is a rear elevational view thereof; and,

FIG. 7 is a bottom plan view thereof.
